US0D1092467S

(12) **United States Design Patent** (10) Patent No.: US D1,092,467 S
Solberg et al. (45) Date of Patent: ** Sep. 9, 2025

(54) TABLET COMPUTER

(71) Applicant: **reMarkable A/S**, Oslo (NO)

(72) Inventors: **Mats Herding Solberg**, Oslo (NO);
Jon Dalvang, Oslo (NO); **Henning Rekdal Nielsen**, Oslo (NO); **Anton Ingvaldson**, Oslo (NO)

(73) Assignee: reMarkable AS, Oslo (NO)

(**) Term: 15 Years

(21) Appl. No.: 29/916478

(23) Filed: Nov 13, 2023

(51) LOC (15) Cl. 14-02

(52) U.S. Cl.

USPC D14/341; D19/113

(58) Field of Classification Search

USPC D14/331, 336, 341–343, 378–380, 129,

(57) CLAIM

The ornamental design for a tablet computer, as shown and described.

DESCRIPTION

FIG. 1 is a FRONT and RIGHT perspective view of a first embodiment of a tablet computer;
FIG. 2 is a FRONT elevation view thereof;
FIG. 3 is a REAR view thereof;
FIG. 4 is a LEFT view thereof;
FIG. 5 is a RIGHT view thereof;
FIG. 6 is a TOP-side view thereof;
FIG. 7 is a BOTTOM-side view thereof;
FIG. 8 is a FRONT and RIGHT perspective view of a second embodiment of a tablet computer;

FIG. 9 is a FRONT elevation view thereof;
FIG. 10 is a REAR view thereof;
FIG. 11 is a LEFT view thereof;
FIG. 12 is a RIGHT view thereof;
FIG. 13 is a TOP-side view thereof;
FIG. 14 is a BOTTOM-side view thereof;
FIG. 15 is a FRONT and RIGHT perspective view of a third embodiment of a tablet computer;
FIG. 16 is a FRONT elevation view thereof;
FIG. 17 is a REAR view thereof;
FIG. 18 is a LEFT view thereof;
FIG. 19 is a RIGHT view thereof;
FIG. 20 is a TOP-side view thereof;
FIG. 21 is a BOTTOM-side view thereof;
FIG. 22 is a FRONT and RIGHT perspective view of a fourth embodiment of a tablet computer;
FIG. 23 is a FRONT elevation view thereof;
FIG. 24 is a REAR view thereof;
FIG. 25 is a LEFT view thereof;
FIG. 26 is a RIGHT view thereof;
FIG. 27 is a TOP-side view thereof; and,
FIG. 28 is a BOTTOM-side view thereof.
The broken lines in the figures show portions of the tablet computer which form no part of the claimed design.
